METHOD OF MAKING DIAPHRAGMS

Percy L. Clark, Jr., Glencoe, and Carl Waterbury,
Chicago, Ill.

Application April 28, 1939, Serial No. 270,530

2 Claims. (CI. 18—59)

Our invention relates to vaginal diaphragms and particularly to a method of making such diaphragms.

Diaphragms of the class described are provided with stiffening or reinforcing elements in the rim thereof, one type utilizing a coil of spring wire and the other, or Mensinga type, utilizing a flat spring. A drawback in the manufacture of such diaphragms arises out of the difficulty of centering the reinforcing element in the body of rubber constituting the rim. In case the spring member is not centered a portion thereof will be exposed and render the diaphragm unfit for use.

A method of molding in which certain of the difficulties are overcome is disclosed in the patent to John T. Clark, No. 2,111,313 of March 15, 1938, but this method has objections that have been overcome in the method herein disclosed.

The predominant thought in connection with the present improvement is to provide for exact centering of the reinforcing annulus, whereby the diaphragm may be accurately molded in completed form with the exception of an area of substantially 90 degrees of the diameter of the rim, this area being so disposed as to render it easy to apply liquid rubber thereto by hand.

The location of the open or incompletely section of the rim is properly determined by a consideration of the forces generated by the die in the act of distributing the raw rubber used in the molding operation; in other words, the metal annulus should be seated in a recess so located that the force of the flowing rubber will tend to seat the annulus more firmly in the recess rather than to tend to dislocate it. With this consideration in mind I have provided in the lower or male die a seat located outwardly of the arc of curvature of the dome, above the lower limits of the rim groove and not above the transverse axis of the metal reinforcing element. In the case of the spirally wound annulus this serves to define the seat as extending over approximately 90 degrees and located at the lower, outer corner of the rim space. In this position the rubber that is ejected with considerable force and velocity out of the dome cavity into the rim cavity tends to urge the annulus against its seat rather than to displace it. Furthermore, since the coils composing the annulus are spaced apart, the rubber will readily flow directly into and through the coil without being compelled to change direction.

The resulting product is a completely molded diaphragm having at an outer edge a narrow

channel extending over about one quarter of the circumference of the rim. Such a channel while it cannot be filled by dipping the rim in liquid rubber can be quickly filled by hand using a small rod or stylus through which the rubber is transferred to the channel and allowed to run along its length and distribute itself evenly therein.

In the case of diaphragms using the flat spring as a reinforcement the described improvement is of still greater importance. With the seat located as before described the rim is so molded as to leave bare the bottom and a portion of the lower outer edge of the metal band, a substantial lip of rubber extending inwardly below the lower edge of the band. This insures that in applying the liquid rubber in the finishing operation there will be complete and even coverage of the band and a round peripheral edge—something that cannot be secured where the lower edge of the band is seated in a recess in the mold. In that case the bottom edge and the two adjacent sides are bare following the molding operation and a round coating of even thickness cannot be applied in any manner other than by a second molding operation. It will be understood that the reason advanced for the use of the Mensinga diaphragm is that it gives great rigidity against lateral distortion; that is, it may be readily bent out of circular form but cannot be bent out of a plane. To obtain this result the two metal bands constituting the annulus should be of substantial width relative to their thickness—something like a clock spring. When so constructed the rim cannot be made circular in cross section without using a great excess of material, but should be in the form of a flat oval; that is, with an equal thickness of rubber on all sides. Such a rim structure can only be produced in the manner shown herein; that is, where the molding operation results in the formation of a quarter-round channel, which, due to surface tension or capillarity of the liquid rubber, may be filled evenly and with a round contour.

The invention will be more readily understood by reference to the accompanying drawing, in which:

Fig. 1 is a plan view of a diaphragm such as contemplated;

Fig. 2 is a sectional view through a pair of dies arranged in accordance with our invention;

Fig. 3 is an enlarged fragmentary sectional view of one portion of the dies;

Fig. 4 is an enlarged sectional view through

one side of a diaphragm as it comes from the mold, this diaphragm having a helical reinforcing member;

Fig. 5 is a view similar to Fig. 3 showing the arrangement where a flat spring reinforcement is used;

Fig. 6 is a view similar to Fig. 4 showing the semicomplete diaphragm that is made in the dies shown in Fig. 5; and,

Figure 7 is a perspective view showing the finishing operation in which liquid latex is applied to the groove formed in the rim, the groove having been partly filled by rotation of the diaphragm in a counter-clockwise direction.

The diaphragm in question has a dome 10 and a rim 11 containing an annulus of metal acting as a reinforcement.

In molding the article we provide an upper or female die 12 and a lower or male die 13, the die cavity 14 providing for the molding of the dome and the cavity 15 for the molding of the rim. The difficulty in the construction of molded diaphragms has been that of insuring perfect centering of the metal reinforcement and to overcome this difficulty we provide at the outer, lower portion of the rim cavity a seat 16, best shown in Figs. 2 and 3, on which is located an endless coil of wire 17, the respective turns of wire being spaced apart. It will be noted that the annular space between the shoulders 18-19 that defines the extent of the seat is substantially 90 degrees of the circumference of the rim. Thus in the molded product, as shown in Fig. 4, the groove in the rim represents about one quarter of the circumference.

The position of the seat is such that, as indicated in Fig. 3, the body of rubber which is supplied to the mold and which is indicated at 20 in Fig. 2 is caused to flow downwardly and outwardly and to spread into the rim cavity as indicated by the arrows in Fig. 3. The force and velocity of the raw rubber is considerable and the direction of flow is such that the metal annulus is held firmly against the seat, the rubber passing through the coils and filling the cavity completely.

In the construction shown in Figs. 5 and 6, which illustrate the manufacture of Mensinga diaphragms, the lower mold 21 has a recess 22 that is slightly undercut to receive the two flat leaf springs 23 constituting the reinforcement. The upper mold 24 is substantially the same as that shown in Fig. 2. As the rubber is squeezed into the rim cavity the force thereof will tend to press the flat spring outwardly into the undercut space and thus effectually prevent any rise of the annulus in the cavity. The resulting product shown in Fig. 6 is the same in all essentials as that shown

in Fig. 4, since in each thereof there remains after the molding operation a quarter round groove that may readily be filled with liquid rubber. In practice, after the molded product has been cured, the diaphragm is held in an inclined position by grasping the dome as shown in Fig. 1 and a quantity of liquid rubber is applied by a stylus or similar instrument 24 in such manner that it fills the groove as indicated by dotted lines in Figs. 4 and 6 and any excess runs along the groove. Thus in the finally completed product there is no possibility of an imperfect article; that is, one in which the metal reinforcement is exposed or not covered with an adequate thickness of rubber. The annulus being held in a definite position, it is certain to be covered fully on all of its sides except for the quarter round bare section, and this being covered by individual hand work, is easily filled due to the shape and location of the groove.

In the Mensinga diaphragm it is important to note that this arrangement provides that the lower edge of the flat springs is not open on both sides, since it would be impractical if not impossible to cause the liquid rubber to flow around the projecting metal body.

It should be understood in examining Figs. 3 to 6 that the views are very greatly enlarged and that some of the dimensions are exaggerated; for example, the flat springs in the Mensinga diaphragm are about the thickness of paper.

We claim:

1. The method of making a diaphragm having a metal reinforcement in its rim, which consists in pressing raw rubber between dies to mold the article in one operation and exposing said reinforcement through an open groove around said rim, said groove being located at a side of a vertical line through the center of said reinforcement and occupying substantially 90 degrees of the circumference of said rim, then curing said molded article, and then, by a manual operation, running liquid rubber in said groove to fill the same.

2. The method of making a diaphragm having an annulus of metal in its rim which consists in supporting the annulus in a mold in such position that the flow of rubber laterally outward toward the rim under the pressure of the molding dies tends to hold the annulus in its seat, the annulus being bare in the molded product to the extent of the width of the seat therefor and less than one-half of the diameter thereof, then curing the molded product, and then, by a manual operation, running liquid rubber into the open space around said rim.
